UNITED STATES PATENT OFFICE

99,251

DESIGN FOR A HANDLE ADAPTED FOR A FAUCET OR SIMILAR ARTICLE

John Tjaarda, Birmingham, Mich., assignor to
Briggs Manufacturing Company, Detroit,
Mich., a corporation of Michigan

Application August 7, 1935, Serial No. 57,995

Term of patent 14 years

To all whom it may concern:

Be it known that I, John Tjaarda, a subject of the Netherlands, residing at Birmingham, county of Oakland, State of Michigan, have invented a new, original, and ornamental Design for a Handle Adapted for a Faucet or Similar Article, of which the following is a specification, reference being had therein to the accompanying drawing, forming a part thereof, in which

Fig. 1 is a top plan view showing my new de-

sign for a handle adapted for a faucet or similar article; and

Fig. 2 is a side elevation thereof.

I claim:

The ornamental design for a handle adapted for a faucet or similar article, substantially as shown.

JOHN TJAARDA.
